COMBINED CONDIMENT STAND AND SHAKERS

Ute Berger, 75 Wandersmannstrasse Weisbaden-
Erbenheim, Germany

Filed Apr. 15, 1971, Ser. No. 134,527

Claims priority, application Germany Oct. 15, 1970

Term of patent 14 years

Int. Cl. D7—01

U.S. Cl. D7—56

FIG. 1

FIG. 2

FIG. 3

FIG. 4

FIG. 5

FIG. 6

FIG. 7

FIG. 8

FIG. 1 is a front perspective view of a combined condiment stand and shakers showing my new design;

FIG. 2 is a side elevation as seen from the right of FIG. 1;

FIG. 3 is a rear perspective view;

FIG. 4 is a side elevation as seen from the left of FIG. 1;

FIG. 5 is a front perspective view of the condiment stand, the shakers removed for convenience of illustration;

FIG. 6 is a front perspective of the shakers;

FIG. 7 is a rear perspective of FIG. 5; and

FIG. 8 is a rear perspective of FIG. 6.

The bottom of both the condiment stand and the shakers is plain and unornamented.

I claim:

The ornamental design for a combined condiment stand and shakers, as shown and described.
